UNITED STATES PATENT OFFICE.

CHARLES H. DERRY, OF ALLIANCE, OHIO.

DESIGN FOR A RADIOCABINET.

Application filed July 18, 1925. Serial No. 14,136. Term of patent 14 years.

To all whom it may concern:

Be it known that I, CHARLES H. DERRY, a citizen of the United States, residing at Alliance, in the county of Stark and State of Ohio, have invented a new, original, and ornamental Design for Radiocabinets, of which the following is a specification, reference being had to the accompanying drawing, forming part thereof.

Figure 1 is a perspective view of the radiocabinet showing my new design thereon; and Fig. 2 is a plan view of the radiocabinet.

I claim:

The ornamental design for a radiocabinet as shown.

CHARLES H. DERRY.
